UNITED STATES PATENT OFFICE

153,911

DESIGN FOR A SOLID FUEL BURNING ROOM HEATER

De Witt H. Wyatt, Columbus, Ohio

Application March 20, 1948, Serial No. 145,248

Term of patent 14 years

(Cl. D81—19)

To all whom it may concern:

Be it known that I, De Witt H. Wyatt, a citizen of the United States, residing at Columbus, in the county of Franklin and State of Ohio, have invented a new, original, and ornamental Design for a Solid Fuel Burning Room Heater, of which the following is a specification, reference being had to the accompanying drawing, forming a part thereof.

Fig. 1 is a perspective view of a solid fuel burning room heater, showing my new design; Fig. 2 is a top plan view thereof; and Fig. 3 is a side elevational view.

I claim:

The ornamental design for a solid fuel burning room heater, substantially as shown.

DE WITT H. WYATT.
